UNITED STATES PATENT OFFICE

2,651,332

THREAD HOLDER FOR LOOMS

Richard G. Turner, Worcester, Mass., assignor to
Crompton & Knowles Loom Works, Worcester,
Mass., a corporation of Massachusetts

Application April 1, 1952, Serial No. 279,738

14 Claims. (Cl. 139—257)

1

This invention relates to thread holder mechanism for weft replenishing looms and it is the general object of the invention to provide such a mechanism which will be in thread non-clamping position on normal non-replenishing beats of the loom but which on a weft replenishing beat of the loom will move to thread clamping position to hold the thread of the transferred bobbin to insure self-threading of the freshly replenished shuttle when it is picked.

In order to effect self-threading of the shuttle of a weft replenishing loom it is desirable to have the thread holder for the weft ends of reserve bobbins in the magazine in a position sufficiently to the rear so that as the shuttle is picked out of the shuttle box under the magazine the thread from the thread holder will be more or less aligned with the shuttle eye. Many looms of the weft replenishing type however are provided with a center filling stop motion fork on the lay and if the thread holder remains in rear position too long there is likelihood that the thread of the freshly replenished shuttle will be behind the fork and not support it with resultant unnecessary loom stoppage.

In order to prevent this stoppage means have already been proposed for controlling the thread holder so that it can be in rearward position at the time of shuttle picking and then be moved to a forward position to draw the thread under the filling fork. Means for accomplishing this result are shown for instance in my prior Patent No. 2,531,177. In that patent the thread holder is of the pneumatic type, but in the present instance it is of the mechanical clamping type.

It is an important object of the present invention to provide a clamping and releasing thread holder having a movable jaw the position of which with respect to a jaw fixed on the thread holder is determined by a controller mounted to move bodily with the thread holder. The controller has abutting engagement with a stationary stop to hold the thread holder in open or non-clamping position under normal conditions, but when the thread holder moves rearwardly the controller is moved to relax its control of the movable jaw and the latter can then be moved to clamping position by means such as a spring.

It is a further object of the invention to construct the controller so that it can be moved out of engagement with the stop to enable the thread holder to continue to move rearwardly after the jaws are in clamping position.

It is a further object of the invention to provide a unit including a thread holder and a sup-

2

porting arm therefor provided with a controller to determine the position of the movable jaw.

In order that the invention may be clearly understood reference is made to the accompanying drawings which illustrate by way of example the two embodiments of the invention and in which:

Fig. 1 is a side elevation of part of a weft replenishing loom having the preferred form of the invention applied thereto,

Fig. 2 is an enlarged side elevation of the thread holder proper showing the latter in open or non-thread clamping position,

Figs. 3, 4 and 5 are detailed horizontal sections on lines 3—3, 4—4 and 5—5, respectively, Fig. 2,

Fig. 6 is a vertical section on line 6—6, Fig. 2,

Fig. 7 is an enlarged view of a part of the structure shown in Fig. 1, setting forth part of the carrier for the thread holder,

Fig. 8 is a horizontal section on line 8—8, Fig. 7 and illustrates the manner in which the wire of the flexible controller for the movable jaw moves with respect to its stop,

Fig. 9 is a diagrammatic view showing the thread holder in normal forward non-clamping position in full lines and in rearward clamped position in dotted lines,

Fig. 10 is a diagrammatic plan of part of the lay showing the shuttle and lay and also the thread holder, the conditions for picking being shown in full lines and the conditions for flight of the shuttle being indicated in dotted lines,

Fig. 11 is a side elevation of a modified form of the invention,

Fig. 12 is a rear elevation looking in the direction of arrow 12, Fig. 11, and

Fig. 13 is a detail plan view, enlarged, looking in the direction of arrow 13, Fig. 11.

Referring to Fig. 1, the loom frame 1 supports top and bottom shafts 2 and 3 which may be connected by conventional gears 4 and 5. The top shaft will ordinarily rotate once for each one-pick cycle of the loom and operates by usual means to reciprocate the lay L backwardly and forwardly, to the right and left as viewed in Fig. 1. The lay is provided with the usual means for receiving a shuttle S and means for picking the shuttle include a picker stick 6 which is actuated in usual manner by lug strap 7.

The loom is provided with a reserve bobbin magazine M which in the present instance is of the stationary multicolor type having several stacks of reserve bobbins B, four stacks being shown in Fig. 1. The reserve bobbins have extending from them weft ends W which lead to a

thread holder designated generally at H. The magazine includes in its construction the usual tie rod 8 which is used herein as a pivotal support.

Under normal conditions the lay swings backwardly and forwardly and when moving rearwardly from its front center position and approximately at its top center position the picker stick will pick the shuttle to the opposite side of the loom and the shuttle will ordinarily be in flight until some time during the ensuing forward motion of the lay. The lay is provided with a center filling fork F, see Fig. 10, which must be supported by weft in order to permit continued loom operation. If for any reason the fork is not supported it will fall and well-known mechanism not set forth herein will then effect loom stoppage. Bobbin transfer mechanism 9, Fig. 1, may be used to transfer a bobbin selected from the magazine into the shuttle on a weft replenishing beat of the loom, preferably as the lay moves forwardly.

The matter thus far described may be of usual construction and operates in the usual manner and except as pointed out hereinafter forms no part of my present invention.

Referring to Figs. 1, 7 and 8, a carrier arm 15 is provided with a bearing hub 16 pivotally mounted on the tie rod 8. A limiting member 17 is secured to the tie rod by a set screw 18 and is formed with depending front and back arms 19 and 20, respectively, between which the arm 15 extends. The lower end of the front arm 19 may be considered to be a stop 21 fixed on the loom forward of arm 15 for a purpose to be set forth hereinafter.

The lower end of arm 15 has secured thereto the previously mentioned thread holder H. The latter includes a rear primary jaw member 25 which is secured by screws 26 to the lower end of arm 15. The primary jaw 25 may be made to extend vertically and back and forth in the loom and may if desired have a thread engaging surface 27 which may be made of soft elastic material, such as rubber. Extending laterally from one side of the jaw 25 are two lugs 30 and 31 located respectively at the right and left as indicated in Fig. 3. These lugs have fitted into them a shield 32 of a flexible wire or controller designated generally at C. A flexible inner core 33 is slidable within the shield.

A secondary movable jaw 35 also having a thread engaging surface 36 similar to the surface 27 is pivoted at its lower end to the primary jaw 25. The pivot may take the form of a pin 37 as shown in Fig. 6. The secondary jaw 35 is provided with a laterally extending lug or abutment 40 which aligns with and is positioned for engagement by the core 33 as shown for instance in Fig. 3. The upper end of the secondary jaw is provided with a head 41 formed with a dependent tongue 42 which fits into an upwardly opening groove or slot 43 formed in the primary jaw 25, see Figs. 5 and 6. The jaws 25 and 35 are provided, respectively, with screws or the like 45 and 46 between which is stretched a tension spring 47 which causes the secondary jaw to have a tendency to move toward the primary jaw, or to the right from the position shown in Fig. 2. Normally the jaws are separated to define an upwardly opening thread slot 48 for the weft ends W. The arm 15 and the thread holder with its jaws may be considered to comprise a thread holder member.

The upper end of the shield 32 is passed through a hub 50 on the arm 15 and is secured

to the hub by set screw 51. The lower end of the shield is fastened to the lugs 30 and 31 by screws 52. The upper end of the core extends beyond the shield, see Fig. 8, and the lower end of the core extends beyond the lower end of the shield. The shield is therefore fixed at its ends with respect to the arm 15 and the core extends beyond each end of the shield. For present purposes it may be considered that the upper end of the core has a free end 55 for abutting engagement with the stop 21 while the lower end of the core has another free end 56 for abutting operative engagement with the lug 40 on the secondary jaw.

A return spring 60 has the rear end thereof connected as at 61 to the arm 15 and has its forward end connected as at 62 to some fixed part of the magazine. The effect of spring 60 is to hold the arm 15 and the holder H normally in the forward position shown in Fig. 1. This position may be determined by a front adjustable stop screw 63 on arm 19. Similarly, if desired a second adjustable stop screw 64 on the rear arm 20 may be used to limit rearward motion of the arm 15. The spring 60 is stronger than the spring 47, but will yield to permit rearward motion of the carrier arm 15.

An actuator rod 65 is connected to arm 15 at 66 and extends rearwardly. The actuator 65 may be operated in any approved manner and may for instance be similar to link 67 shown in the previously mentioned patent. The actuator 65 need not however be operated necessarily by the structure set forth in that patent and it will be sufficient for the purposes of the present invention if the actuator locates arm 15 rearwardly at or about the time of shuttle picking on a weft replenishing beat of the loom and then moves to effect return forward motion of arm 15 by spring 60 a short time after the shuttle is picked.

Under normal conditions the arm 15 and the holder will be as shown in Fig. 1 and in full lines in Fig. 9, that is, they will be in forward position and the primary free end 55 of the core will be held firmly against the stop 21 by spring 60 and the latter will hold the core in a relatively rearward position with respect to that part of the shield shown for instance in Fig. 8. The effect of this relation is to cause the lower secondary free end 56 of the core to exert a forward push on lug 40 to hold the secondary jaw 35 in the open or non-thread clamping position shown in full lines in Fig. 9 against the action of spring 47. Under these conditions the weft ends W can pass freely through the upwardly opening thread slot 48 and the lower ends of the threads may be wadded together as at 67 to exert a downward pull on the weft ends to hold them taut. These conditions will prevail on non-replenishing beats of the loom and the thread holder will be in a relative forward position with respect to the sweep of the lay.

When a weft replenishing operation occurs actuator 65 will move rearwardly and swing arm 15 from the full line to the dotted line position shown in Fig. 8, thereby moving the controller C rearwardly to relax the force previously exerted rearwardly by stop 21 against the primary free end 55 of the core. The weak spring 47 is therefore free to contract and draw the secondary jaw toward the primary jaw as indicated in dotted lines in Fig. 9 to clamp the weft ends. This operation will ordinarily occur so that the weft ends can be clamped at the time of picking 70 of the shuttle to insure proper anchorage for

the thread of the bobbin which has been freshly inserted into the shuttle.

The shuttle, which is of the self-threading type, is then picked and preferably during its flight the actuator 65 moves forwardly, thereby enabling the spring 60 to move the arm 15 forwardly and force free end 55 of the core against stop 21 to effect forward movement of lug 40 by free end 56 to restore the thread holder to its normal non-clamping position shown in full lines in Fig. 9. This return of the thread holder to its normal forward position preferably occurs late enough in the cycle of the loom to insure proper unwinding of the weft on the freshly transferred bobbin and also occurs at a time favorable for movement 15 of the weft end leading from the shuttle to a position under the filling fork F.

In Fig. 10 it is assumed that the lay is in picking position as shown in full lines and that the thread holder will be in relatively rear position, full lines, so that the weft end W1 leading from the thread holder to the freshly transferred bobbin B1 will be aligned more or less with the shuttle at the start of the pick. Thereafter the lay moves rearwardly to the dotted line position of Fig. 10, the shuttle moves along the lay to the dotted line position, and the thread holder moves forwardly to the dotted line position, the effect of these movements of the lay, shuttle and thread holder being to move the thread of the shuttle to position W2 under the filling fork to support the latter.

In the modified form of the invention shown in Figs. 11 to 13 much of the matter thus far described will be used but the controller C1 for the secondary jaw, instead of being a flexible wire, is a lever. As shown more particularly in Fig. 11 an arm 70 similar to arm 15 is pivoted as is the latter arm and has the primary and secondary thread engaging jaws 25 and 35, respectively, mounted thereon as in the preferred form. The spring 47 normally urges the secondary jaw toward the primary jaw as is the case in the preferred form.

The controller C1 comprises a lever 71 pivoted to the arm 70 at 72. Lever 71 has an upwardly extending arm 73 formed with a free end 74 for abutting engagement with the stop 21. A second arm 75 depends from the pivot 72 and as shown in Fig. 13 engages the abutment or lug 40 of the secondary jaw. The spring 60 normally holds the arm 70 to the left as viewed in Fig. 11.

In the operation of the modified form of the invention the spring 60 holds the end 74 of lever 71 in abutting engagement with the stop 21 and causes the lever to assume a position relative to arm 70 such that the lower free end 76 of arm 75 will exert a forwardly directed force against the lug 40 to hold the secondary jaw spaced from the primary jaw in a non-clamping position. The weft ends can therefore move freely through the thread slot 48. When the actuator 65 moves the arm 70 rearwardly the lever 71 moves pivotally in such manner that its lower end 76 moves rearwardly to relieve the force which it exerts on the lug 40 and the spring 47 is thereupon able to move the secondary jaw toward the primary jaw to clamping position to grip the weft ends. When the arm 70 has a return movement to its normal forward position lever 71 will be rocked in the opposite direction with respect to the arm 70 and the lower free end 76 of lever 71 will again exert a forward force on lug 40 to move the secondary jaw to open position spaced forwardly from the primary jaw.

In both forms of the invention a controller is provided for the secondary or pivoted jaw 35 and the controller is normally held in abutting engagement with stop 21 to maintain the slot 48 open, but when the carrier arm, either 15 or 70, moves rearwardly the controller moves with respect to its arm to enable spring 47 to move jaw 35 toward jaw 25 and in clamping relation with respect to the weft ends. It will be noted in both forms of the invention that if the amount of rearward motion of the carrier 15 or 70 needed for correct placement of the thread holder to facilitate shuttle threading is greater than the amount needed to close the slot 48 the free end 56 of the controller can move away from the stop 21 without straining the controller or any other part of the mechanism. In fact, it may be desirable to have the free end of the controller always move away from stop 21 as the thread holder moves to its rear position, since this will insure clamping of the weft ends an appreciable time before picking of the freshly replenished shuttle.

From the foregoing it will be seen that the invention sets forth a simple thread holder mechanism including a controller which operates incident to back and forth movement of the thread holder member to effect closing of slot 48 to clamp the weft ends as the thread holder moves rearwardly and open the slot to unclamp the weft ends as the thread holder moves forwardly. The free end of the controller which abuts stop 21 can move away from the stop to enable the thread holder to continue its rearward movement after the jaws are in clamping position. When the thread holder returns to its forward position the free end of the controller strikes the stop 21 and the secondary jaw is thereupon moved forwardly to open slot 48. There is also set forth a thread holder unit for mounting on a tie rod of a magazine. In the preferred form of the invention there is no anchorage for the core with respect to any part of the loom, and in the modified form the upper arm of the controller lever 71 is not directly attached to stop 21. While the spring 60 has been shown for effecting return movement of the arms 15 and 70 to their normal forward position the invention is not necessarily limited to this spring and it will be sufficient for the purposes of the invention if the thread holder member moves first in a rearward direction, to the right in Fig. 1, incident to a weft replenishing operation, and thereafter has a return movement to the left to forward position. It is to be understood that the invention is not limited to the use of rubber for establishing clamping relation with respect to the threads passing through the slot 48.

Having now particularly described and ascertained the nature of the invention and in what manner the same is to be performed, what is claimed is:

1. In thread holder mechanism for the weft ends of a weft replenishing loom, a stop forming part of the thread holder mechanism, a weft end thread holder member which on a weft replenishing beat of the loom moves to a rearward position and thereafter moves to a forward position, said thread holder member comprising a primary thread engaging jaw and a secondary thread engaging jaw mounted on the thread holder member for movement toward and from the primary jaw and having a normal tendency to move toward the primary jaw, and a controller for the secondary jaw mounted on and moving with the thread holder member having one part

thereof operatively related to the secondary jaw and having another part rearward of said stop for abutting engagement therewith, said other part being held against said stop by the thread holder member when the latter is in forward position and causing said controller to overpower said tendency of the secondary jaw and hold the secondary jaw spaced from the primary jaw, and said thread holder when moving to the rearward position thereof moving said other part of the controller away from said stop and said secondary jaw due to said tendency thereupon moving toward the primary jaw.

2. The thread holder mechanism set forth in claim 1 wherein the controller comprises a flexible wire having a shield secured to the thread holder member and a flexible core slidably within the shield and operatively connected to both the stop and the secondary jaw when the thread holder member is in forward position and is operatively connected to the secondary jaw only when the thread holder member is in rearward position.

3. The thread holder mechanism set forth in claim 1 wherein the controller comprises a lever pivoted on the thread holder member having an arm for engagement with the stop and another arm for engagement with the secondary jaw.

4. The thread holder mechanism set forth in claim 3 wherein the lever is pivoted intermediate said arms thereof and is moved bodily relatively to the stop by said thread holder member when the latter moves from one of said positions thereof to the other of said positions thereof.

5. In thread holder mechanism for the weft ends of a weft replenishing loom, a stop forming part of the thread holder mechanism, a weft end thread holder member which on a weft replenishing beat of the loom moves to a rearward position and thereafter moves to a forward position, said thread holder member comprising a primary thread engaging jaw and a secondary thread engaging jaw mounted on the thread holder member for movement toward and from the primary jaw, resilient means normally tending to move the secondary jaw toward the primary jaw, a controller for the secondary jaw mounted on and moving with the thread holder member having one end thereof operatively related to the secondary jaw and having another end rearward of said stop for abutting engagement therewith, said other end being held against said stop by the thread holder member when the latter is in forward position and said controller being operative due to abutting engagement with said stop to overpower said resilient means and hold the secondary jaw spaced from the primary jaw, and said thread holder when moving to the rearward position thereof moving said other end of the controller away from said stop and said resilient means moving the secondary jaw toward the primary jaw.

6. In thread holder mechanism for the weft ends extending from the bobbin magazine of a weft replenishing loom, a stop forming part of the thread holder mechanism, a thread holder member mounted for movement on the magazine and comprising a primary thread engaging jaw fixed to the thread holder member and a secondary jaw mounted on the thread holder member for movement toward and from the primary jaw, resilient means normally tending to move the secondary jaw toward the primary jaw, a controller supported by and movably mounted on the thread holder member having a part

5 thereof operatively connected to the secondary jaw, a spring normally holding the thread holder member toward the stop with another part of the controller in abutting engagement with the stop and causing the first named part of the controller to act in opposition to said resilient means to hold the secondary jaw spaced from the primary jaw, and an actuator operative on a weft replenishing beat of the loom to move the thread holder member and controller away from the stop, said resilient means thereupon moving the controller relatively to the thread holder member and moving the secondary jaw toward the primary jaw.

7. In thread holder mechanisms for the weft ends of a weft replenishing loom, a stop forming part of the thread holder mechanism, a weft end thread holder member which on a weft replenishing beat of the loom moves to a rearward position and thereafter moves to a forward position, said thread holder member comprising a primary thread engaging jaw fixed to the member and a secondary thread engaging jaw mounted on the member for movement toward and from the primary jaw, resilient means normally tending to move the secondary jaw toward the primary jaw to thread clamping position, a controller for the secondary jaw supported by and movably mounted on the thread holder member positioned for abutting engagement with said stop and held in such engagement when the thread holder member is in the forward position thereof and being effective due to said engagement to overpower the resilient means and hold the secondary jaw spaced from the primary jaw, said thread holder member when moving to the rearward position thereof moving the controller out of abutting engagement with said stop to enable said resilient means to move the secondary jaw toward the primary jaw.

8. In thread holder mechanisms for the weft ends of a weft replenishing loom, a stop forming part of the thread holder mechanism, a thread holder member for the weft ends which on a weft replenishing beat of the loom moves to a rearward position and thereafter moves to a forward position, said thread holder member comprising a primary thread engaging jaw and a secondary thread engaging jaw movable toward and from the primary jaw, resilient means normally tending to move the secondary jaw toward the primary jaw to thread clamping position, and a controller for the secondary jaw operatively connected to the latter and positioned for abutting engagement with the rear of the stop when the thread holder member is in forward position and effective due to a rearwardly directed force exerted on the controller by said stop when the thread holder member is in forward position to overpower the resilient means and hold the secondary jaw spaced from the primary jaw, the thread holder member when moving to rearward position reducing the rearwardly directed force exerted by the stop on said controller and the resilient means thereupon moving the secondary jaw toward the primary jaw.

9. In thread holder mechanism for the weft ends of a weft replenishing loom, a stop forming part of the thread holder mechanism, a thread holder member for the weft ends which on a weft replenishing beat of the loom moves to a rearward position and thereafter moves to a forward position, said thread holder member comprising a primary thread engaging jaw and

a secondary thread engaging jaw movable toward and from the primary jaw, resilient means normally tending to move the secondary jaw toward the primary jaw to thread clamping position, and a flexible wire moving with the thread holder member and including a shield secured to the thread holder and a core slidably within the shield operatively interposed between the stop and secondary jaw effective due to a rearwardly directed force exerted on the core by said stop when the thread holder member is in forward position to overpower the resilient means and hold the secondary jaw spaced from the primary jaw, the thread holder member when moving to rearward position reducing the rearwardly directed force exerted by the stop on said core and the resilient means thereupon moving the secondary jaw toward the primary jaw.

10. In thread holder mechanism for the weft ends extending from the bobbin magazine of a weft replenishing loom, a stop forming part of the thread holder mechanism, a thread holder member mounted for movement on the magazine and comprising a primary thread engaging jaw fixed to the thread holder member and a secondary jaw pivoted with respect to the thread holder member and movable toward and from the primary jaw, resilient means normally tending to move the secondary jaw toward the primary jaw, a flexible wire having one end thereof secured to the thread holder member rearward of said stop and having the other end thereof secured to the thread holder member adjacent to said jaws, said flexible wire including a flexible core slidably within the shield and having a free end projecting beyond said one end of the shield for abutting engagement with said stop and having another free end projecting beyond the other end of the shield for engagement with said secondary jaw, means acting on said thread holder normally urging said one end of the shield forwardly toward said stop and holding said one end of the core in abutting engagement with said stop to cause the other end of the core to hold said secondary jaw spaced from the primary jaw, and an actuator operative on a weft replenishing beat of the loom to move said thread holder in a direction to move said one end of the shield and said free end of the core for engagement with said stop rearwardly away from said stop and thereby enable said resilient means to move the secondary jaw toward the primary jaw.

11. In thread holder mechanism for the weft ends of a weft replenishing loom having a self-threading shuttle to be replenished by a reserve bobbin, the loom having a lay provided with a center filling stop motion fork, a stop forming part of the thread holder mechanism, a thread holder member for said weft ends which on a 60 weft replenishing beat of the loom moves from a forward position to a rearward position favorable for self-threading of the shuttle when the

latter is picked subsequent to replenishment and thereafter returns to forward position to favor movement of the thread of the replenished shuttle under the filling fork, said thread holder member including a primary thread engaging jaw and a secondary thread engaging jaw mounted on the thread holder member for movement toward and from the primary jaw and having a tendency to move toward the primary jaw, and 5 a controller for the secondary jaw mounted on and moving with the thread holder member and having abutting engagement with the rear of said stop when the thread holder member is in forward position and effective due to said engagement to cause the stop to exert a rearwardly directed force on said controller the effect of which is to cause the controller to hold the secondary jaw spaced from the primary jaw, the thread holder member when moving to the rearward position thereof moving the controller therewith and reducing said force to enable the secondary jaw to move toward the primary jaw to clamping position relative to the weft end and the thread holder member thereafter continuing to move to the rearward position thereof and moving the controller away from said stop.

12. In a thread holder unit for a reserve bobbin magazine provided with a pivotal support, an elongated thread holder member provided at one 30 end thereof with a bearing for the pivotal support and having a primary thread engaging jaw fixed to the other end thereof and a secondary jaw mounted on the member for movement toward and from the primary jaw, resilient means 35 normally tending to move the secondary jaw toward the primary jaw, and a controller mounted on the member for movement relative thereto having one end thereof for operative relation with the secondary jaw and having the other 40 end thereof free for application thereto of a force in a given direction effective to cause the controller to move the secondary jaw away from the primary jaw against the action of said resilient means.

13. The thread holder unit set forth in claim 12 wherein the controller is a flexible wire comprising a shield secured to the member and a flexible core slidable in the shield.

14. The thread holder unit set forth in claim 12 wherein the controller is a lever pivoted on the member having an arm for operative engagement with the secondary jaw and having another arm provided with said free end.
